UNITED STATES PATENT OFFICE.

CHARLES A. NELSON, OF CHICAGO, ILLINOIS, ASSIGNOR TO C. A. NELSON CO., OF CHICAGO, ILLINOIS, A CORPORATION OF ILLINOIS

INCANDESCENT-LAMP-BULB SOCKET.

1,262,237.

Specification of Letters Patent. Patented Apr. 9, 1918.

Application filed May 22, 1916. Serial No. 99,207.

To all whom it may concern:

Be it known that I, CHARLES A. NELSON, a citizen of the United States, residing at Chicago, in the county of Cook and State 5 of Illinois, have invented certain new and useful Improvements in Incandescent-Lamp-Bulb Sockets, of which the following is a specification.

This invention relates to improvements in 10 incandescent lamp bulb sockets, and it has for its salient object to provide a simplified construction in which the use of blocks or masses of porcelain, hard rubber, etc., is eliminated and all, or substantially all, of 15 the interfitting parts made of sheet material capable of being pressed or stamped into the desired form; to provide a construction in which a maximum amount of space is provided in the interior chamber in which 20 the attachment of the leading-in wires to the terminals is effected, to the end that such attachment and detachment may be more conveniently accomplished and with less danger of short circuiting; to provide a construction which is extremely economical 25 both of manufacture of the parts and assemblment thereof; to provide a construction which because of its simplicity and manner of construction is extremely durable 30 and free from liability of getting out of order; and in general, to provide an improved device of the character referred to.

The invention will be readily understood 35 from the following description, reference being had to the accompanying drawing, in which—

Figure 1 is an axial sectional view of the improved socket;

Fig. 2 is a cross-sectional view taken in 40 the plane of the line 2—2.

Describing the preferred embodiment of my invention, and referring to the drawing, 1 designates an outer generally cylindric shell, the respective end portions of which 45 differ somewhat in diameter; the two portions of different diameter being joined by an inclined shoulder 2 which serves as a stop or seat for internal parts, as hereinafter described. The shell 1 is provided with a 50 lining 3 of insulating sheet material, as for example red fiber, and which conforms to the interior of the shell. The larger end of the body shell is closed by a slip-cover or cap 4, around the center of which is formed 55 a neck-like extension 5 in which is seated the

insulating thimble 6. The cap is also provided with a lining of sheet insulating material 7 conformed thereto.

Describing now the internal mechanism, 8 and 9 designate respectively two cup-shaped sheet metal members which are arranged base to base in axial alignment with each other, insulated from each other, and secured together by a series of rivets 10, 11 and 12. The larger cup member 8 constitutes the supporting member which carries the rest of the internal mechanism, and it has its lower or closed end seated against the inclined shoulder 2 hereinbefore mentioned. It is preferably somewhat smaller in external diameter than the interior of the insulating lining 3 and is centered or interspaced within said insulating lining by means of a series of external longitudinally extending ribs 8' (see Fig. 2). 75

At diametrically opposite points, wall portions of said cup member 8 are struck in by means of dies to form embracing clips 13 integral with the main body of the cup. These clips embrace and hold the respective 30 terminal strips 14, 15; the terminal strips being insulated from the clips by interposed sheet insulation 16. Preferably, and as shown herein, the cup member 8 is lined with sheet insulating material 17 formed 85 into cup-shape and fitting accurately the interior of the member 8; the insulation interposed between the terminal strips and the clips 13 being formed of flaps struck out from the inner insulating shell 17 in a manner similar to the formation of the clips 13 as parts of the cup member 8. 90

Each of the terminal strips has an inturned outer end portion in which the corresponding binding screw is inserted whereby 95 the leading-in wires 18 and 19 are connected. Terminal strip 14 has a tongue 14' struck out of its interior portion and extending at right angles across the axis of the socket member, while terminal strip 15 has its 100 lower end bent at right angles inwardly to overlie the insulation on the bottom of the cup-member 8 and has direct metallic connection with the rivet 11. A separate metal plate 20 is mounted upon and insulated from the bottom of the cup member 8 and has direct metallic contact with the rivet 10 which extends through said plate and through a U-shaped contact member 21 arranged within the smaller cup member 9. A contact 110

spring 22 is mounted upon plate 20, and this contact spring and the opposed tongue 14' coöperate with a metal bridging switch button 23 which is mounted upon the end of 5 a thumb shaft 24 extending out through the side of the socket and provided with the usual thumb nut.

The smaller cup member 9 constitutes the socket proper in which the shank of the 10 lamp bulb is inserted, being to this end pressed into screw threaded form, as usual.

The circuit through the socket member and bulb is as follows: from leading-in wire 19 to terminal strip 14, through tongue 14', 15 to switch button 23, thence to contact strip 22, plate 20, rivet 10, spring contact 21 to the central or internal contact of the lamp bulb, through the filament to the shell of the lamp shank which screws into direct 20 metallic contact with the cup 9. The return circuit is from cup 9, through rivet 11, terminal strip 15 and leading-in wire 18. Turning the switch button ninety degrees 25 opens the circuit between the tongue 14' and contact strip 22.

It will be understood from the foregoing description that my improved device may be most economically and conveniently constructed and assembled. The outer shell and 30 slip cover or cup thereof may be separately fitted with said respective linings. The cup member 8 may be provided with its insulating lining and the terminal strips properly mounted and secured in place therein. The 35 two cups may then be placed base to base and the insulation and rivets inserted, and the two parts permanently joined, after which the internal unit so formed may be inserted in place within the shell and all 40 secured rigidly in place by the simple placing of the cap 4 upon the outer shell. Obviously the internal mechanism unit may be withdrawn from the shell with equal ease, for the purposes of inspection, repair or for 45 more conveniently attaching the leading-in wires to the terminals.

It will be obvious that the details of construction and arrangement may be modified without departing substantially from the 50 invention as herein shown and described. The appended claims, therefore, are to be

construed in a manner commensurate with their terms and the state of the prior art.

I claim as my invention:

1. In an incandescent lamp socket, an 55 outer shell, a pair of cup-shaped members secured together at their bases, contact holding clips formed from one of said cup-shaped members, and the other of said cup-shaped members formed to constitute the 60 lamp holding shell.

2. In an incandescent lamp socket, an outer shell formed of sheet metal, a pair of sheet metal cup-shaped members connected 65 base to base and insulated from said outer shell, and a cap for said outer shell for securing the parts together.

3. In an incandescent lamp socket formed of sheet metal stampings, an outer supporting shell, an inner cup-like shell seated within and insulated from said outer shell, contact-holding clips formed from said inner shell and lying within the latter, contact-strips held by said clips, a lamp-receiving shell, a spring-contact supported therein, 75 rivets connecting the bases of the lamp shell and the inner shell, and a contact device mounted on the base of the inner shell and electrically connected with the contact of the lamp-receiving shell. 80

4. In an incandescent lamp socket, an outer shell formed of sheet metal and having a shoulder intermediate its ends, an inner shell insulated from said outer shell and adapted to be supported by the shoulder 85 on said outer shell, contact-holding clips formed from said inner shell, contact strips secured in said clips, said strips having their upper ends bent to form binding posts, a lamp-receiving shell insulated from said 90 outer shell, a plurality of rivets for securing said lamp-receiving shell to said inner shell, one of said rivets being the electrical connection between one of said strips and said lamp-receiving shell, and a cap for the upper end of said outer shell for securing the parts together. 95

CHARLES A. NELSON.
